(57) **CLAIM**

The ornamental design for a medical bed, as shown and described.

DESCRIPTION

FIG. 1 is a front, right perspective view of a medical bed; FIG. 2 is a rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of area 9 shown in FIG. 1; and, FIG. 10 is an enlarged view of area 10 shown in FIG. 2.

The broken lines shown on the drawings depict portions of the medical bed that form no part of the claimed design.
